UNITED STATES PATENT OFFICE.

ELWOOD J. HARPER, OF LOUISVILLE, KENTUCKY, ASSIGNOR TO HARPER ADJUSTABLE GUIDE COMPANY, OF LOUISVILLE, KENTUCKY, A CORPORATION OF KENTUCKY.

ADJUSTABLE GUIDE FOR RULING MACHINES.

Application filed February 7, 1927. Serial No. 166,448.

This invention relates to a novel adjustable or shiftable guide attachment for ruling machines.

My primary aim is to provide an attachment for a machine of this character, wherein the attachment is such in construction as to operate as a time saver, as well as a saver for material and labor.

An equally important object is to obviate the disadvantages of using shifting clamps, beams, and guide cords after the pins are set.

An advantage and purpose is to perfect an absolutely accurate guiding means for the sheet of paper, so that the sheet may be delivered evenly and uniformly to the inking pens, thus assuring proper registration of the lines.

A still further object is to provide a guide of this character which is adjustable from a small fraction of an inch to approximately seven and one-half inches, and which is such that when it is once set, it cannot be accidentally moved unless readjusted by the operator.

An additional object is to provide a structure of this kind which is characterized by compactness and convenience of arrangement of parts, so adjusted and related as to insure efficiency and practicability.

Other features and advantages of the invention will become apparent from the following description and drawings.

In the accompanying drawings forming a part of this application, and in which like numerals are employed to designate like parts throughout the same:

Figure 1 is a fragmentary top plan view of a portion of a ruling pen machine showing the attachment (in dotted lines) associated therewith.

Fig. 2 is an end view of the same.

Fig. 3 is a top plan view of the attachment per se, removed from the machine.

Fig. 4 is an enlarged detail section taken approximately upon the plane of the line 4-4 of Fig. 3, and

Fig. 5 is an enlarged detail sectional view taken approximately on the line 5-5 of Fig. 3.

Considering now the drawings in detail, and confining attention first to the old parts of a conventional type of ruling machine, it will be seen that the reference character A designates the usual guide cord which co-

operates with the grooved guide cord roll 55 B. A part of the frame is represented at C and this is provided with a grooved guide cord roll bearing at D. The customary operating crank for turning the ruling machine is indicated at E. At F a portion of the frame is indicated, and at G is a bolt for holding the frame. The character H represents a support for the customary feed board, the latter being represented by the reference character I.

The usual center string roller is indicated by the reference character J. The dotted bolts K extend through the guide board, feed board, and feed board brace, represented by the reference character P. The guide board 70 is represented at L. The reference character N (see Fig. 1) is representative of an adjusting screw for the guide board straight edge M. In addition, O represents a part of the frame, and Q a pair of spaced parallel slots 75 formed in the feed board I.

The attachment or shiftable guide device, is attached to the under side of the feed board L as best shown in Fig. 2. The device by itself however, as more plainly represented in Fig. 3, wherein it will be seen that the same comprises a pair of duplicate spaced parallel shafts 1 rigidly pinned at one end to a connecting strip 2, and fastened at the opposite end to a similar but slightly longer connecting strip 3. I employ a pair of right angle brackets 4 to connect the strip 2 to the feed board.

In this connection, I would state that I employ wood screws for this purpose, the brackets being suitably connected to the connecting strip or member 2. Similar brackets 5 are fastened to the member 3 and the horizontal portions thereof are slotted to form forks which are fastened to the bolts 95 K which extend through the brace bar P. These four parts 1, 2 and 3, form a frame-like support for a carriage which is represented generally by the reference character 6. This carriage includes a travelling bar 100 7 which has its opposite ends slidably mounted on the shaft 1. To accomplish this, I form openings in the ends of this part 7 and extend the reduced end portions of the sliding sleeves 8 through these openings 105 the sleeves being slidably mounted on the shafts 1, 1.

In this connection, it will be noted that

the bar member 7 is provided at its center with an opening (see Fig. 4) through which a bushing 9 extends. This bushing is internally screw threaded, and has operating 5 connection with a centrally located feed screw 10. The feed screw is located at a central point between the two shafts 1 and has its opposite ends rotatably mounted in the connecting members 2 and 3 respectively. 10 More specifically, the opposite end portions of the feed screws are reduced and swivelly mounted in the connecting members 2 and 3. The swivel mounting of the left hand end of the feed screw 10 is shown in Figure 15 3 in dotted lines, while the corresponding mounting of the opposite end of the same screw is shown in Figure 4.

The inner end of the bushing 9 is externally screw threaded, and a collar 11 is 20 fitted onto the same to provide a connection between it and the travelling bar 7. While considering the last named figure, it will be noticed that a knurled finger nut 12 is pinned or otherwise rigidly secured to the feed 25 screw 10 and it is obvious that by rotating this nut, the screw will rotate and will, thru the medium of the bushing 9, move the traveling bar 7 and its sleeves 8 back or forth on the shafts 1, according to the direction of rotation of the nut.

Attention is now invited to the provision of the straight edge or shiftable guide element 13 which forms a part of the sliding carriage and which is connected thereto by 35 means of a pair of upstanding standards 14. As shown in Figs. 4 and 5, the upper ends of these standards have studs fitting into sockets in the under edge of the straight edge. This shiftable guide element 13 is in 40 its normal position, disposed in abutting relation with the guide board straight edge M as shown for example in Figure 1.

Also as shown better in Fig. 5, the traveling bar 7 is provided with vertical screw 45 threaded holes through which an elevating screw 15 passes. This screw is connected with standards 14 and it is provided at its bottom with a handle 16 and above this is a lock nut 17. It is obvious that by rotating 50 the screw 15, the adjacent standard 14 can be elevated in order to raise or lower the shiftable guide element 13.

At this time, I would call attention to the 55 fact that this guide element is located above the top of the feed board I and that the standards 14 extend upwardly through the slots Q in this feed board. Hence, as before stated, the guide can be adjusted from a small fraction of an inch to approximately 60 seven and one-half inches along the surface of the feed board toward or from the guide board straight edge M.

Attention is invited to the fact that when 65 setting the pens to rule equally spaced unit columns, every other column is set. There-

fore, it is necessary to run the sheet through the ruling machine the second time. Before doing so, the straight edge of the shiftable guide is moved back or forth (depending upon the position of the straight edge when starting), the distance between columns for second running. After ruling loose leaf sheets, from binding edge, reversing the same to rule other side requires approximately ten seconds to adjust guide in order 70 that the lines will register. Should change in temperature cause sheets of paper to contract or expand, it would not be necessary to move the clamps as under ordinary conditions. Shifting of the guide back or forth 75 will make the lines register.

It is believed that by considering the foregoing description in connection with the drawings, a clear understanding of the invention and construction, method of attachment, and operation will be clear. Therefore, a more lengthy description is thought unnecessary.

While the preferred embodiment of the invention has been shown and described, it 90 is to be understood that minor changes coming within the field of invention claimed may be resorted to if desired.

Having thus described my invention, what I claim as new is—

1. In a structure of the class described, in combination, a ruling machine embodying, among other parts, a feed board, a guide board associated therewith, and a supplemental manually adjustable guide and 100 straight edge device, movable toward and from said guide board and across the top of said feed board, and manually adjustable means for said supplemental guide being supported from the under side of said feed 105 board.

2. In a structure of the class described, in combination, a ruling machine including, a feed board provided with a pair of spaced 110 parallel slots, a shiftable guide element movable across the upper side of the feed board, supporting standards for said element connected thereto and extending downwardly through said slots, and supporting and adjusting means for said standards mounted 115 on the under side of said feed board.

3. In a ruling machine attachment of the class described, a pair of spaced parallel shafts, connecting members between said shafts for maintaining them in assembled relation, attaching brackets for said connecting members, a feed screw located between said shafts and rotatably connected at its opposite ends with said connecting members, a shiftable guide element, and a carriage 120 therefor slidably upon said shafts and having operating connection with said feed screw.

4. In a ruling machine attachment of the class described, a pair of smooth surfaced 125

- spaced parallel shafts, members connecting said shafts together in assembled parallelism attaching brackets, for connecting said members with a part of the ruling machine, a feed screw located between said shafts and rotatably connected at its opposite ends with said connecting members, sleeves slidably mounted on said shafts, a traveling bar connected at its outer end portions with said sleeves, a screw threaded bushing carried by the central portion of said traveling bar, said bushing being adapted to move along said screw to carry said bar and sleeves with it, means for rotating said screw, a shiftable guide element and means whereby said shiftable guide element is connected with said traveling bar.
5. In a ruling machine attachment of the class described, a pair of smooth surfaced spaced parallel shafts, members connecting said shafts together in assembled parallelism, attaching brackets, for connecting said members with existing parts of the ruling machine, a feed screw located between said shafts and rotatably connected at its opposite ends with said connecting members, sleeves slidably mounted on said shafts, a traveling bar connected at its outer end portions with said sleeves, a screw threaded bushing carried by the central portion of said traveling bar, said bushing being adapted to move along said screw to carry said bar and sleeves with it, means for rotating said screw, a shiftable guide element, means whereby said shiftable guide element may be connected with said traveling bar, and adjusting screws associated with said traveling bar for allowing vertical adjustment of said connecting means.
- 10 sleeves, a screw threaded bushing carried by the central portion of said traveling bar, said bushing being adapted to move along said screw to carry said bar and sleeves with it, means for rotating said screw, a shiftable guide element and means whereby said shiftable guide element is connected with said traveling bar.
- 15 5. In a ruling machine attachment of the class described, a pair of smooth surfaced spaced parallel shafts, members connecting said shafts together in assembled parallelism,
- 20

In testimony whereof I affix my signature.

ELWOOD J. HARPER.
